UNITED STATES PATENT OFFICE.

GODFREY STAIGER, OF TOLEDO, OHIO.

DESIGN FOR A LOWER MEMBER FOR BUSHINGS.

SPECIFICATION forming part of Design No. 28,027, dated December 14, 1897.

Application filed September 21, 1896. Serial No. 606,586. Term of patent 14 years.

To all whom it may concern:

Be it known that I, GODFREY STAIGER, of Toledo, county of Lucas, and State of Ohio, have invented a certain new and original 5 Design for Lower Members of Bushings for Bungs; and I do hereby declare that the following is a full, clear, and exact description of the invention, which will enable others skilled in the art to which it appertains to make and 10 use the same, reference being had to the accompanying drawing, and to the letters of reference marked thereon, which forms part of this specification.

This is a design for the lower member of a 15 two-part bushing for bungs. The drawing represents a perspective view of the same.

The leading feature of my design consists of a lower member or section of a bushing, the said member having an annular concavo- 20 convex rim and a cylindrical body, the latter being provided with external and internal screw-threads, the external threads being of

greater depth and pitch than the internal threads, as illustrated.

A designates the cylindrical body, and B 25 the concavo-convex upturned rim of the member, which is cast therewith and on the lower end thereof, the convexity being downward and the concavity upward, as in the case of a hat-rim. The said cylindrical body is provided with external screw-threads *a* and 30 internal screw-threads *a'*, the former having the greater depth and pitch.

What I claim is—

The design for the lower member of a bushing for bungs substantially as shown and 35 described.

In testimony that I claim the foregoing as my own I hereby affix my signature in presence of two witnesses.

GODFREY STAIGER.
